ABSTRACT: A reinforced concrete slab formed to provide a rugged support when resting on soft soil to form a runway for aircraft or the like, said slab being formed of reinforced concrete and provided with reinforced concrete projections shaped to form pockets for the reception of soil, said projections being resistant to bending and being secured rigidly to the underside of the slab.

FIG. 2

FIG. I

A 4x6 grid of plus signs, arranged in four rows and six columns.

FIG. 3a

A 4x4 grid of 16 'X' characters, arranged in four rows and four columns.

FIG. 3b

H H H H
H H H H
H H H H
H H H H
H H H H

FIG. 3c

A 3x3 grid of nine T-shaped blocks. Each block is composed of a vertical line segment with a horizontal crossbar at its midpoint. The blocks are arranged in three rows and three columns.

FIG. 3d

A 4x5 grid of diagonal lines forming a diamond pattern. The lines are black and intersect to create a series of diamond shapes. The grid is composed of 20 lines in total, arranged in a 4x5 configuration.

REINFORCED CONCRETE SLAB RESTING ON SOFT GROUND

This application is a continuation-in-part of U.S. application Ser. No. 556,731, filed June 10, 1966 now abandoned.

This invention relates to a reinforced concrete slab formed to provide a rugged support when resting on soil to form a roadway for vehicles, a runway for aircraft or a foundation for a machine or building.

The construction of runways for aircraft in poor or soft soils always requires a considerable amount of earthmoving firstly for excavation of the soft soil to the depth of 1.5 to 2.0 meters, depending upon the aircraft loading, secondly for the transportation of the excavated soft soil, and thirdly for the arrival of sand to replace the excavated soft soil.

The layer of sand beneath the actual runway is of a thickness of 1.50 to 2.0 meters and serves to distribute the wheel pressures of the aircraft over such a large area of the soft soil beneath the layer of sand that the permissible pressure on the soil—which is of the order of 0.2 to 0.3 kg./cm.² is not exceeded. To satisfy this requirement, the layer of sand has to be kept dry by means of a good drainage system.

The earthmoving requires a considerable amount of heavy equipment, so that first of all the required access roads have to be constructed over the said poor soils. After the required soil stabilization and sand filling have been provided an extensive and good system of drainage pipes is fitted to keep the sand course dry. The construction of the actual runway cannot start until this has been done, and the runway consists of a hard course about 0.50 meters thick of sand and rock with a surfacing of about 30 cm. cement concrete. The said thicknesses of the courses depend upon the maximum aircraft load.

It will be apparent that the said operations require a considerable amount of material transport. The object of the invention is considerably to reduce the costs for material transport and construction time by completely eliminating all the preparatory and associated work, such as soil stabilization by means of sand filling and the construction of an extensive and good drainage system to keep the sand course dry. To this end, the invention provides a reinforced concrete slab formed to provide a rugged support when resting on soft soil to form a runway for aircraft or the like, said slab being formed of reinforced concrete and provided with reinforced concrete projections shaped to form pockets for the reception of soil, said projections being resistant to bending and being secured rigidly to the underside of the slab, said slab having a thickness of the order 8 to 25 centimeters, said projections having a width of about 1 to 2 meters and a length of about 1 to 5 meters and being spaced apart about 1.2 to 4 meters.

According to the invention, the function of the said sand course is taken over completely by a relatively thin slab of reinforced concrete provided with an efficient stiffening system formed by the projections, so that the relatively thin slab of reinforced concrete, which can be 8 to 20 cm. thick, can properly carry out its pressure-distributing function. This stiffening system is distinguished by its simple form and composition, and also by the simplicity and convenience of its construction. This simplicity and convenience of construction are at a maximum in soft soils where the soil water level is high.

The quantity of concrete to be used for constructing a slab according to the invention is small. This small quantity can be decreased by applying projections deriving their stiffness in all vertical planes substantially from their form.

The projections preferably consist of tubes.

It is advantageous for the projections to extend to a greater depth at the edges of the slab than the projections at the center thereof.

The invention also provides a method for constructing a slab according to the invention. This method is characterized by the following successive steps:

inserting prefabricated projections in the soil and pouring a layer of reinforced concrete over said projections. The prefabricated projections can easily be inserted even in very soft soil, particularly in morass.

The projections may consist of prefabricated round tubes of reinforced concrete. The outside diameter, length and spacing will depend upon the nature of the soft soil and the maximum loading expected on the slab, which will be explained in the following description with reference to the accompanying drawing, wherein:

FIG. 1 is a top plan view of part of a runway according to the invention.

FIG. 2 is a cross section on the line II-II in FIG. 1.

FIGS. 3a—3f diagrammatically illustrate a number of examples of cross sections and formations of projections of other slabs according to the invention.

FIG. 4 shows diagrammatically a plan view of a slab according to the invention.

FIG. 5 is a side view of the slab according to FIG. 4 and FIG. 6 is a side view on larger scale of the part V of FIG. 5.

When it is required to construct a runway in an area where the firm soil 1 has an overlying course of soft or poor soil 2, for example of a compressive strength of 0.2 to 0.3 kg./cm.², prefabricated reinforced concrete tubes 3 are recessed into the soft soil 2. Each tube 3 is recessed into the soil as follows: the soil within the upright tube is first excavated in layers either manually or mechanically. As the excavation of the soil advances, the tube is advanced into the soil until the required depth has been reached. The excavated soil, which during excavation was temporarily piled around the circumference of the tube, is then completely returned to the original plane inside the tube and tamped down well until the tube is completely embedded rigidly and immovably in the ground to the depth shown in FIG. 2. In some cases, for example in very soft soil, the relatively lightweight and short tubes can easily be driven into the ground.

Once all the tubes 3 have been fitted, the steel reinforcement of the slab 4 is twisted in known manner and the concrete is then poured as for an ordinary floor slab. It must be expressly pointed out that care must be taken to ensure a rigid and immovable connection between the slab and the tube so as to prevent any angular turning between the tube and the slab. To this end, the reinforcing wires of the tubes can project at the top, form the prefabricated concrete and act as anchors or hooks in the slab 4. The top edges of the tubes 3 may also project somewhat above the soil in these tubes.

No drainage system whatever is required in the ground, since the slab 4 is adapted to transmit the wheel pressure of the heaviest aircraft to the subsoil in its natural state over an adequately wide area.

The tubes 3 are not intended to transmit the wheel pressures of the aircraft on the slab to the firm soil via the tubes as is the case with well foundations. In actual fact the tubes 3 are as it were suspended in the soft soil from the slab 4. No further explanation is necessary to show that this new method of applying stiffened reinforced concrete slabs to soft soils—particularly when the water level is high—can be carried out much more simply and quickly than in the conventional manner using main and bridging joists of reinforced concrete. The stiffening action of the tubes 3 on the slab 4 is due to the fact that when the soil beneath the slab is loaded it is so compressed by the tubes that it cannot escape laterally, so that the slab 60 remains stiff as it were.

The above-described runway or road has the very important advantage that it requires no reinforcing or stiffening for increasing wheel loads, since the heavier wheel pressure simply has to be transmitted by the same slab over a larger area to the soft soil while with conventional runways and roads a complete reinforcement or thickening of the pressure-distributing sand course and of the roadway itself is necessary.

Although round tubes are preferably, square or other tubes having angular cross sections can be used as projections.

The invention also covers slabs for which the projections are not formed by tubes. FIG. 3 shows a number of examples of cross sections of formations of such projections.

The projections derive their stiffness substantially from their form preferably not only in one vertical plane, like the projections of FIG. 3e but in all vertical planes, like the projec-

tions of FIGS. 3a, 3b, 3d and 3f and particularly like the projections of FIGS. 1 and 2.

FIG. 6 shows the part VI of the slab of FIG. 5.

The dimensions of the slab according to the invention, which are indicated in FIG. 6 are for example as listed in examples I and II. In examples I and II the security factor $n=1.5$. However, the dimensions may be calculated with a security factor 1.2 resulting in smaller projections 3 or with a security factor 2.0 resulting in larger projections 3.

In this example the pitch distance between two adjacent projections = a .

The load is for example an equally distributed load p .

The height of the projections = h .

The width of the projections = b .

The specific weight of the soil together with the ground water possibly found therein = c .

The internal friction angle of the soil concerned = Φ .

EXAMPLES I

The security factor $n=1.5$

The pitch distance a of adjacent projections = 2 m.

The width b of the projections = 1.2 m.

C	φ	p	h
specific weight of soil (ton/m. ³)	friction angle of soil (°)	specific load (ton/m. ²)	height of projections (m.)
1.8.....	10	1.5	2.07
		2	2.28
		2.5	2.45
		3	2.60
2.....	10	1.5	2.00
		2	2.20
		2.5	2.36
		3	2.52
1.8.....	15	1.5	2.00
		2	2.22
		2.5	2.38
		3	2.54
2.....	15	1.5	1.88
		2	2.08
		2.5	2.23
		3	2.38
1.8.....	20	1.5	1.82
		2	2.05
		2.5	2.16
		3	2.30
2.....	20	1.5	1.78
		2	1.94
		2.5	2.10
		3	2.22

EXAMPLES II

The security factor $n=1.5$.

The pitch distance $a=2.5$ m.

The width of projections $b=1.5$ m.

C	φ	p	h
specific weight of soil (ton/m. ³)	friction angle of soil (°)	specific load (ton/m. ²)	height of projections (m.)
1.8.....	10	2	2.64
		2.5	2.82
		3	3.00
		3.5	3.16
2.....	10	2	2.65
		2.5	2.74
		3	2.90
		3.5	3.06
1.8.....	20	2	2.34
		2.5	2.50
		3	2.67

		3	2.58
		3.5	2.72

WALL THICKNESS

In these examples I and II the wall thicknesses of the tubes are so computed, that they are rigid enough to withstand bending load.

In the above examples I and II the wall thickness w of the tubes = 8 cm.

SLAB THICKNESS d

In the above examples I and II a slab thickness of $d=10$ à 12 cm. is required. This slab has such a small thickness owing to the fact that the span length between two adjacent projections which is equal to pitch distance a is so small.

EXAMPLE III

The security factor $n=1.1$.

The specific load p is 1 ton/m.².

The specific weight of the soil $c=2.1$.

The internal friction angle of the soil $\Phi=25^\circ$.

The pitch distance $a=4$ m. and the length $h=1$ m.

EXAMPLE IV

The security factor $n=2.0$.

The specific load p is 5 ton/m.².

The specific weight of the soil $c=1.7$.

The internal friction angle of the soil $\Phi=9^\circ 4$.

The distance $a=1.5$ m. and the width $b=1.2$ m.

EXAMPLE V

The security factor $n=1.1$.

The specific load p is 1 ton/m.².

The specific weight of the soil $c=2.1$.

The internal friction angle of the soil $\Phi=25^\circ$.

The slab thickness $d=25$ cm.

The width $b=1$ m.

EXAMPLE VI

The security factor $n=2.0$.

The specific load $p=5$ ton/m.².

The specific weight of the soil $c=1.7$.

The internal friction angle of the soil $\Phi=10^\circ$.

The length $h=5$ m. and the width $b=2$ m.

As the slab according to the invention is practically stiff the slab can be loaded by a point load P which is equal to the product of the specific load p and the slab area RL .

What I claim is:

1. A reinforced concrete slab formed to provide a rugged support when resting on soft soil to form a runway for aircraft or the like, said slab being formed of reinforced concrete and provided with reinforced concrete projections shaped to form pockets for the reception of soil, said projections being resistant to bending and being secured rigidly to the underside of the slab, said slab having a thickness of the order 8 to 25 centimeters, said projections having a width of about 1 to 2 meters and a length of about 1 to 5 meters and being spaced apart about 1.2 to 4 meters.

2. Slab according to claim 1, characterized in that the projections are of tubular configuration.

3. Slab according to claim 1, wherein said reinforced concrete projections have reinforcing wires projecting therefrom which are imbedded in the concrete slab.

4. Slab according to claim 1 characterized in that the projections in the middle of the slab are shorter than the projections situated nearer the edges of the slab.

5. A reinforced slab as claimed in claim 1 wherein the slab thickness within the projections of tubular configuration is greater than the slab thickness between said projections.

6. A reinforced concrete slab formed to provide a rugged support when resting on soft soil to form a runway for aircraft or the like, said slab being formed of reinforced concrete and provided with reinforced concrete projections shaped to form pockets for the reception of soil, said projections being resistant to bending and being secured rigidly to the underside of the slab, said slab having a thickness of the order 15 to 20 centimeters, said projections having a width of about 1 to 1.5 meters and a length of about 1 to 3 meters and being spaced apart about 2 to 3 meters.

7. Slab according to claim 6, characterized in that the projections are of tubular configuration.

8. Slab according to claim 6, wherein said reinforced concrete projections have reinforcing wires projecting therefrom which are imbedded in the concrete slab.

9. Slab according to claim 6, characterized in that the projections in the middle of the slab are shorter than the projections situated nearer the edges of the slab.
